UNITED STATES PATENT OFFICE.

LEE S. CHADWICK, OF CLEVELAND, OHIO, ASSIGNOR TO THE CLEVELAND METAL PRODUCTS COMPANY, OF CLEVELAND, OHIO, A CORPORATION OF OHIO.

WICK-STOP.

1,258,395.

Specification of Letters Patent.

Patented Mar. 5, 1918.

Application filed August 2, 1915. Serial No. 43,139.

To all whom it may concern:

Be it known that I, LEE S. CHADWICK, a citizen of the United States, residing at Cleveland, in the county of Cuyahoga and 5 State of Ohio, have invented a certain new and useful Improvement in Wick-Stops, of which the following is a full, clear, and exact description, reference being had to the accompanying drawings.

10 This invention relates to that class of oil burners comprising, generally, an inner and an outer wick tube between which a wick is guided and above which commingling tubes are supported in operative 15 relation to the wick, the commingling tubes being inclosed in a drum. Suitable means for supplying oil to the wick is communicatively connected to one of the wick tubes; and further means is employed for elevat- 20 ing and lowering the wick.

More particularly, the invention relates to a wick stop for burners of the class above referred to; and it has for its object the provision of a highly efficient wick stop that 25 may be economically manufactured and which, in its preferred form, may be dropped into the upper end of the inner wick tube and allowed to settle by gravity into its proper position, the wick stop and 30 the aforesaid wick tube having coöperating portions which interlock as the stop assumes its final position, thereby to effectually hold the stop against elevation.

In the accompanying drawings I have 35 illustrated a wick stop associated with a burner of the above mentioned type, and wherein the above, and other objects which will become apparent as this description proceeds, are attained. During the course of 40 the specification I will describe in detail the wick stop shown herein, although I wish to be understood as not limiting myself to the structural details thereof further than is required by the terms of the annexed claims 45 and is rendered necessary by the state of the prior art.

In the drawings, Figure 1 is a central vertical section through an oil burner equipped with a wick stop of my invention; Fig. 2 is 50 a plan view of the burner and wick stop, with the commingling tubes and drum removed; Fig. 3 is a horizontal sectional view on the line 3—3 of Fig. 1, and looking in the direction of the arrows, the drum being 55 omitted from this figure; Fig. 4 is a central

sectional detail through the upper portion of the wick tubes and wick and shows the wick stop and coöperating parts of the wick tube in elevation; and Fig. 5 is a perspective view of the wick stop.

Taking up a detailed description of the invention by the use of reference characters, 1 represents the outer and 2 the inner wick tube which are connected by having the lower end of the outer wick tube turned inward and upward into contact with the inner wick tube, as shown at 3, the overlying portions of the wick tubes being preferably soldered to seal the wick space inclosed by the tubes, against leakage. A short distance 60 below their upper ends and in about the same horizontal plane, the outer and inner wick tubes are provided with ledges 5 and 6, respectively, whereon the lower ends of the respective outer and inner commingling 65 tubes 7 and 8 are arranged to rest. The commingling tubes are shown as connected together in the usual manner by the rods 9 and 10, and these rods also support the drum 11, that is shown as provided with a 70 handle 12, whereby the drum may be conveniently manipulated.

The inner commingling tube has a perforated cover 15, and its lower end is provided with a perforated diaphragm 16, having a centrally located thimble 17, the recess 18 of which opens downward for the reception of the upper end of a lifter rod 20 that is guided through a strap 21 that spans the inner wick tube, near its lower 75 end, and through the circular wall 22 of an inverted cup-shaped member 23, supported from the wall of the inner wick tube by braces 24, that may be riveted to the cylindrical wall of the aforesaid member, as 80 shown at 25, and fastened to the wick tube by soldering or other suitable means. The lower end of the lifter rod 20 is turned laterally through a slot 27 within a depending portion 28 of the strap 21. This drum 85 lifting mechanism constitutes no part of my present invention, and it is therefore deemed unnecessary to describe it further, although it will be stated, in order to avoid 90 any possible confusion as to the physics and theory of operation of the burner, that the strap 21 is narrow and does not, in any way, obstruct the free passage of air upward through the inner wick tube. The outer 95 wick tube has secured to it the usual wick 100

raising means, shown generally at 30, which coöperates with the metallic sheath 31 that surrounds and is connected to the lower end of the wick 32.

5 The wick stop is shown generally at 40, and comprises an annulus to which the reference numeral 40 is applied, and which is made up of a vertical wall and a horizontal wall that are substantially at right angles 10 to each other. This annulus constitutes the body portion of the wick stop, and from the upper edge of its vertical wall project the stop fingers 41. These fingers extend upward and then outward over the path 15 of the wick, and determine its maximum elevation. Depending from the inner periphery of the annulus are anchorage members or hooks 42, their front and rear edges 43 and 44, respectively, diverging upwardly 20 from their rounded lower ends. The front edge of each anchorage member is cut inward a short distance from its lower end, and then upward, to produce a hook or shoulder 45.

25 It will be observed that the cup-shaped member 23 consists of two cylindrical portions of varying diameters wherefore a horizontal, annular wall 47 is formed, and this wall is provided with a series of slots 48 30 into which the lower ends of the anchorage members 42 are arranged to descend, as the annulus of the wick stop settles by gravity into contact with the ledge 6 of the inner wick tube. Attention is invited to the fact 35 that the length of the slots 48 are substantially equal to the horizontal dimension of the anchorage members in the zone of their shoulders 45.

40 When the wick stop is inserted into the inner wick tube, it requires only sufficient attention on the part of the operator to see that the lower ends of the anchorage members enter the slots. This may be accomplished by the operator simply placing the wick stop within the wick tube until the 45 lower ends of the anchorage members abut the wall 47 of the member 23, whereupon the wick stop may be rotated until the anchorage members are felt to pass downward through the slots. As soon as this proper 50 registration is made, the remainder of the operation becomes automatic, for the gravity of the stop will cause it to descend, and the inclination of the front and rear edges 55 of the anchorage members will cause them to find their proper position with respect to the slots 48. For example, if the anchorage members enter the slots so that their front edges 43 come into contact with the 60 corresponding ends of the slots, the wick stop will be rotated backward until the points adjacent the shoulders 45 pass the aforesaid ends of the slots and drop beneath the same. Immediately, the rotation of the member will be reversed by the engagement

of the rear edges 44 of the anchorage members with the opposite ends of the slots 48, said inclined edges 44 acting as cams to actively project the shoulders 45 beneath the adjacent ends of the slots. When in this 70 position, the wick stop is held against appreciable upward movement, so that the wick may be elevated by the means 30 until its upward movement is arrested by the fingers 41.

75 While it was explained that the lower ends of the commingling tubes rest upon the edges 5 and 6 it will be understood from the illustration that, when the wick stop is present, the horizontal wall of its annulus 40 80 will contact directly with the ledge 6 of the inner wick tube, while the lower end of the commingling tube 8 will rest upon the upper surface of said horizontal wall. A slight relative longitudinal movement between the commingling tubes is provided by making the apertures of the inner commingling tube through which the rods 9 and 10 pass, slightly elongated, as illustrated. The 85 same result would obviously be accomplished if the reverse were true and the outer commingling tube provided with the elongated openings.

90 It is clear that the cup-shaped member 23 serves the three fold purpose of guiding the lifter rod 20, of forming a lock for the wick stop, and of deflecting the air which rises through the inner wick tube and directing it into close proximity to the upper end 95 thereof, thereby to retain the temperature 100 of the wick tube at the minimum degree. However, as far as my present invention is concerned, any means which will answer the purpose of retaining the wick stop against 105 elevation, and which will coöperate with the anchorage members thereof substantially in the manner described, will be considered the full equivalent of the cup-shaped member, so long as it falls within the terms of the 110 annexed claims.

Having thus described my invention, what I claim is:—

1. The combination with a burner of the class described, the inner wick tube whereof is provided with a ledge adjacent its upper end, of an annulus which is arranged to be inserted into the upper end of said wick tube and repose upon said ledge, the annulus having a plurality of fingers which radiate therefrom and overlie the path of the wick, a member supported within the inner wick tube and below the aforesaid ledge, said member having a wall that extends transversely of the inner wick tube and that is provided with a plurality of slots, the annulus having a plurality of depending anchorage members that are adapted each to enter one of the aforesaid slots, each anchorage member having opposed edges which diverge upwardly, one of said edges having a 130

shoulder that is adapted to be projected beneath the aforesaid wall adjacent one end of the slot when the other edge of said member engages and traverses the opposite end of the slot.

2. The combination with a burner of the class described having a support within the inner wick tube, of an annulus arranged to repose upon said support, the annulus having a plurality of fingers which overlie the path of the wick, opposed abutments supported within the inner wick tube, the annulus having an anchorage member that is adapted to enter between said abutments and having opposed edges which diverge upwardly, one of said edges having a shoulder that is projected beneath one of the abutments when the other edge of said member engages and traverses the opposite abutment.

3. The combination with a burner of the class described, the inner wick tube whereof

is provided with a ledge adjacent its upper end, of an annulus arranged to repose upon said ledge, the annulus having fingers that overlie the path of the wick, a member supported within the inner wick tube below the aforesaid ledge and having a wall extending transversely of the wick tube and that is provided with slots, the annulus having depending anchorage members arranged to enter said slots, each anchorage member having opposed edges which diverge upwardly, one of said edges having a shoulder that is projected beneath the aforesaid wall adjacent one end of the slot when the other edge of said member engages and traverses the opposite end of the slot.

In testimony whereof, I hereunto affix my signature in the presence of two witnesses.

LEE S. CHADWICK.
